MACHINE FOR REMOVING LACINGS FROM
SHOE UPPERSJoseph Fossa, Lynn, Mass., assignor to United
Shoe Machinery Corporation, Paterson, N. J.,
a corporation of New Jersey

Application March 5, 1937, Serial No. 129,213

20 Claims.

(Cl. 12—1)

The present invention relates to a machine for operating upon temporary lacings in lasted shoes, and more particularly to a machine for severing lacings of the type formed by the machine disclosed in inventor's prior application for U. S. Letters Patent Serial No. 21,011, filed May 11, 1935, which machine is constructed and arranged to apply a plurality of individually fastened lengths of cord extending across the eyeleted edges and through eyelets in opposite sides of a shoe upper.

In certain types of temporary lacings for holding the upper of a shoe stretched in close fitting relation to a last, a single length of cord is passed through all of the eyelets and tied with a knot at the ends so that to release the last from the shoe it is necessary to sever the cord at one point only. In the type of lacing formed by the machine referred to, each pair of adjacent eyelets in opposite sides of the shoe upper are connected together by a separate length of cord, each length being passed through the eyelets to form a plurality of parallel strands and each strand being individually fastened. To completely release the last from a shoe, the eyelets of which are connected by lacings of this type, all of the strands of every lacing must be severed. On account of being drawn tightly against the support provided by the convex surfaces of the last during the lasting operation, the lacings are held firmly in contact with the underlying finished surfaces of the shoe and of the tongue of the shoe. It is frequently difficult for this reason to separate all of the strands from the underlying surfaces sufficiently to avoid accidental marking of the shoe or otherwise injuring the surfaces while severing the strands. The operation of releasing the last, when the shoe is held stretched by a lacing of this type may, therefore, in certain instances, require so much time and care as to render the operation objectionably expensive.

It is, therefore, an object of the present invention to provide a machine for severing the lacings of a shoe quickly and reliably without marking or otherwise injuring and, accordingly, an important feature of the invention includes the provision in a machine having devices for severing the lacings, of means for locating the shoe in proper relation to the machine before the lacings are severed so that the severing devices may operate quickly and effectively without being brought into accidental contact with the finished surfaces of the shoe. In the form of the invention illustrated, the means for locating the shoe in proper relation to the machine comprises a number of

hook members, each engaging a lacing before said lacing is severed.

Other features of the invention include the provision of means for gripping each lacing so that each lacing may be withdrawn completely from the upper without leaving behind any of the separate strands of mechanism for operating the severing devices successively; of connections between the hook members for changing quickly the spacings between them by equal amounts when the eyelets of successive shoes operated upon are separated differently; and of means for removing the severed lacings from the gripping means before a new shoe is presented to the machine.

The several features of the present invention and the advantages to be obtained thereby will readily be understood by one skilled in the art from the following description taken in connection with the accompanying drawings in which Fig. 1 is a view in right side elevation, partly broken away and in section of a lacing machine embodying the features of the invention and indicating the position of a lasted shoe held in the machine; Fig. 2 is a plan view of the machine illustrated in Fig. 1; Fig. 3 is a perspective view of an operating unit of the machine arranged with the parts including the gripper bar, the hook member and the cutter plate shown in separated relation; Fig. 4 is a view in front elevation, partly broken away and in section of the machine; Fig. 5 is a sectional view taken along the line 5—5 of Fig. 2; Fig. 6 is a sectional view taken along the line 6—6 of Fig. 2; Fig. 7 is a sectional view taken along the line 7—7 of Fig. 2; Figs. 8 and 9 are detail plan views of certain parts of the machine shown with a shoe located in operative position and with the lacings severed respectively; Fig. 10 is a vertical sectional view taken along the line 10—10 of Fig. 9; Fig. 11 is a similar view illustrating the position assumed by the lacing after the shoe has been removed from the machine and Fig. 12 is a similar view showing the lacing being removed from the operating unit.

The machine illustrated in the drawings is arranged with a series of parallel operating units for severing and gripping all of the strands of a number of individual lacings 2 as formed on the machine described in the application, above referred to. In this type of lacing, the cord of each lacing passes a number of times through a pair of adjacent eyelets 4 in opposite sides of the upper 6 of a shoe secured in close fitting relation to a last 8 about which it has previously been stretched during a lasting operation. The shoe is first lo-

cated in proper relation to the operating units of the machine and the units then actuated to sever and grip the lacings. Relative movement of the shoe and operating units in removing the shoe 5 from the machine thereafter causes the severed lacings to be withdrawn from the eyelets of the shoe. With this brief outline of the mode of operation of the machine a detailed description of its parts will now be given.

10 Each operating unit, as indicated in Figure 3, comprises a central slidable positioning strip 10, a cutter plate 12 beneath the positioning strip, and a gripper bar 14 above the positioning strip. Each positioning strip is notched at the left side 15 of its forward end to form a hook-like finger 16, the notch forming a finger providing a space within which a lacing may enter and the rear edge of each finger being suitably tapered to facilitate entrance of a lacing into the notch. 20 When a lacing is applied to a hook finger 16, the tension in the lacing imparted while lasting the shoe causes the finger to be wedged between the outer and inner strands of the lacing, the inner strand being supported by the rigidity of 25 the last within the shoe, as shown in Figs. 1 and 8. The forward surface of a finger thus acts to locate both the lacing and the shoe accurately as well as to guard the tongue of the shoe, indicated at 18, from damage while the 30 lacing is being severed. When moved lengthwise, each positioning strip causes the lacing held in the notch at its forward end to be dragged across a sharpened edge 20 of the cutter plate 12 and to be squeezed between the 35 gripper bar 14 and the upper surface of the finger 16.

To secure the parts of each unit together in operative relation, a bolt 22 passes through perforations in each gripper bar and cutter plate 40 and through a lengthwise slot in each positioning strip at the front of the machine. At the central part of each unit is a bolt 24 passing through the gripper bar and cutter plate and through a second lengthwise slot in the positioning strip. All of the units are mounted in 45 the upper part of the open box-like frame 26 of the machine with all of the fingers 16 directed in alignment to facilitate entry of the lacing of a shoe simultaneously into the notches forming the fingers. 50

To move the positioning strips lengthwise, the rearward ends of the strips carry downwardly projecting pins 28. Fulcrumed on a horizontal shaft 30 on the frame beneath the pins 28 is 55 an actuating lever 32 the upper rectangular arm of which is provided with a curved slot 34 along its horizontal portion into which the pins 28 project. To the other arm of the lever 32 is connected a treadle rod 36 having its lower end 60 connected to a foot treadle 38. The treadle rod is pivoted to a floor fixture 40 at its rearward end and at a convenient distance below the level of the machine frame 26. When the treadle is depressed, the hook finger 16 of each 65 unit is actuated, but due to the curvature of the slot 34 in the rectangular arm of lever 32, the fingers cause the separate lacings to be severed successively so that less pressure is required on the treadle during actuation. To maintain the 70 treadle 38 raised, a coil spring 42 is stretched between the treadle and a stationary part (not illustrated). While the treadle is held depressed, a grip is maintained on each severed lacing, as indicated in Fig. 10, so that when the 75 shoe is withdrawn from operative position the

lacings will be pulled loose from the eyelets of the shoe (see Fig. 11). As soon as the treadle is raised the lacings are released from the operating units (Fig. 12), the units then being ready for operation on the new shoe. To prevent the hook fingers from being moved forwardly too far, when the treadle is raised, the operating lever 12 is provided with a short horizontal arm having a set screw 43 engaging the frame 26 and limiting the movement of the 10 lever.

In order that the severed lacings will be withdrawn with certainty from the hook fingers after being freed, there is mounted beneath the forward ends of the operating units, the open end 15 of a suction tube 44 extending through a rectangular opening in the upright arm of operating lever 32. When the hook fingers 16 free the lacings from the gripper bars, the lacings are quickly carried through the suction tube into a 20 suitable collecting container.

In shoes of different sizes or styles, the spacings between eyelets vary to such an extent that the hook fingers 16 may fail to engage the lacings properly unless provision for proper spacing is made. To change the spacings of the hook fingers 16, when different sizes of shoes are operated upon, all the operating units with the exception of the unit at the extreme left are movable in a guideway 45 in the upper part of 30 the frame, and the bolts 24 which hold the units together also pass through right angle arms 46 rigidly connected between the units and pivotally connected at equally separated points to a spacing lever 47. The arms extend across 35 the series of units and serve to position the units along the guideway. The units are held from lengthwise movement in the guideway 45 while being free to move transversely of their length by the engagement of the lower headed ends of 40 bolts 24 in a slot 48 formed in the lower surface of the guideway 45. A pair of guide rods 50 attached at their ends to the frame 26 cover the open upper side of the guideway along the front and rear edges of the frame to hold the bolt heads within the slot 48. The bolt 24 which passes through the extreme left hand unit has its head uppermost, as shown in Fig. 7, and is threaded at its lower end in the frame 26 to hold that unit stationary. To provide a rigid 45 connection of the arms on the bolts 24 in the other units, each gripper bar 14 carries a stud 51 passing through an opening in one end of each arm 46. Successive arms 46 are arranged alternately at one of two levels and are spaced 55 vertically from each other by the use of washers 52 surrounding the bolts 24 and the pivotal connections for the lever 47.

The spacing lever 47 is secured to a vertical shaft 54 rotatably mounted at the right side of 60 the machine in a bearing lug 56 extending from the frame 26. To the central part of the shaft 54 there is pinned a collar 58 (see Fig. 4) bearing on the upper surface of the bearing lug 56 and the lower end of the shaft is threaded to 65 receive check nuts 60 between which and the under surface of the lug is compressed a spring washer 62 for the purpose of holding the spacing lever frictionally in adjusted position during operation of the machine. To adjust the spacing 70 lever there is mounted at the upper end of the shaft 54 a hand crank 64. The construction is such that when the spacing lever is moved from the dot-dash position to the solid line position of Fig. 2, the arms 46 not only move the operating 75

units equally transversely of their length, but also due to their rigid connection with the arms the units are held from turning or twisting in the guideway 45.

5 The nature and scope of the invention having been indicated, and a construction embodying the several features having been described, what is claimed is:

1. A machine for operating upon a lasted shoe, 10 the upper of which is held stretched in close fitting relation to a last by one or more lacings passing through eyelets in opposite sides of the upper comprising cutting means for severing the lacings, and means for locating the shoe in an 15 operative position on the machine before the lacings are severed.

2. A machine for operating upon a lasted shoe, the upper of which is held stretched in close fitting relation to a last by one or more lacings 20 passing through eyelets in opposite sides of the upper, comprising cutting devices for severing the lacings, and a hook member engaging each lacing to locate the shoe in an operative position on the machine before the cutting devices act.

25 3. A machine for operating upon a lasted shoe, the upper of which is held stretched in close fitting relation to a last by one or more lacings passing through eyelets in opposite sides of the upper comprising a cutting device for severing a lacing, and a member to engage a lacing to locate the shoe in an operative position on the machine before the cutting device acts.

30 4. A machine for operating upon a lasted shoe, the upper of which is held stretched in close fitting relation to a last by one or more lacings 35 passing through eyelets in opposite sides of the upper, comprising a cutter for each lacing, a hook member arranged to enter between each lacing and the last to locate the shoe in an operative position on the machine, and connections for relatively actuating the hook members and cutters to sever the lacings.

40 5. A machine for operating upon a lasted shoe, the upper of which is held stretched in close fitting relation to a last by one or more lacings 45 passing through eyelets in opposite sides of the upper, comprising cutting devices for severing the lacings, and means for gripping one end of each severed lacing to cause the lacings to be withdrawn from the eyelets when the shoe is 50 moved relatively to the gripping means.

55 6. A machine for operating on a lasted shoe, the upper of which is held stretched in close fitting relation to a last by one or more lacings passing through eyelets in opposite sides of the upper, comprising cutting devices for severing the lacings, and means for gripping each lacing to cause the severed lacings to be withdrawn from the eyelets by a subsequent relative movement of the gripping means and shoe.

60 7. A machine for operating upon a lasted shoe, the upper of which is held stretched in close fitting relation to a last by one or more lacings passing through eyelets in opposite sides of the upper, comprising devices for severing the lacings and for gripping the lacings to cause the severed lacings to be withdrawn from the eyelets by a subsequent relative movement of the gripping means and shoe.

70 8. A machine for operating upon a lasted shoe, the upper of which is stretched in close fitting relation to a last by one or more lacings passing through eyelets in opposite sides of the upper and across the outer surfaces at the side edges 75 of the upper, comprising cutting means for sev-

ering the lacings, and a series of hook members arranged with their hook portions opening in the same direction towards one end of the series for engaging the lacings along those portions which cross the side edges of the upper to locate the 5 shoe in an operative position on the machine before the lacings are severed.

9. A machine for operating upon a lasted shoe, the upper of which is stretched in close fitting relation to a last by one or more lacings passing through eyelets in opposite sides of the upper and across the outer surfaces at the side edges of the upper, comprising cutting means for severing the lacings, a series of hook members arranged with their hook portions opening in 10 the same direction towards one end of the series for engaging the lacings, cutting means at one side of the series, gripping means at the other side of the series, and connections for relatively actuating the hook members and the cutting and 15 gripping means to sever and grip the lacings.

10. A machine for operating upon a lasted shoe, the upper of which is held stretched in close fitting relation to a last by one or more lacings 20 passing through eyelets in opposite sides of the upper, comprising cutting means for severing the lacings, a hook member engaging each lacing to locate the shoe in an operative position on the machine before the cutting means acts, a bar 25 cooperating with each hook member, and connections for actuating each hook member relatively to each bar to grip one end of each severed lacing and cause it to be withdrawn from the 30 eyelets.

11. A machine for operating upon a lasted shoe, the upper of which is held stretched in close fitting relation to a last by one or more lacings passing through eyelets in opposite sides of the upper, comprising a cutter plate for each lacing, a gripper bar for each lacing and a hook 40 member for causing each lacing to be drawn across the cutting edge of each cutter plate and to be wedged between each adjacent gripper bar and hook member when the hook members are actuated relatively to said cutter plates and 45 gripper bars.

12. A machine for operating upon a lasted shoe, the upper of which is held stretched in close fitting relation to a last by one or more lacings 50 passing through eyelets in opposite sides of the upper, comprising cutting means for severing the lacings, a hook member cooperating with each lacing to locate the shoe in an operative position on the machine before severing the lacings, and means for changing the spacings of 55 the hook members by equal amounts.

13. A machine for operating upon a lasted shoe, the upper of which is stretched in close fitting relation to a last by one or more lacings 60 passing through eyelets in opposite sides of the upper and across the outer surfaces at the side edges of the upper, comprising cutting means for severing the lacings, a guideway, a series of hook members arranged in the guideway with 65 their hook portions in alignment to engage the lacings along those portions which cross the side edges of the upper, and a manually operable member for changing the spacings of the hook members equally along the guideway.

70 14. A machine for operating upon a lasted shoe, the upper of which is stretched in close fitting relation to a last by one or more lacings passing through eyelets in opposite sides of the upper and across the outer surfaces at the side 75 edges of the upper, comprising cutting means for severing the lacings, a guideway, a series of hook members arranged in the guideway with their hook portions in alignment to engage the lacings along those portions which cross the side edges of the upper, and a manually operable member for changing the spacings of the hook members equally along the guideway.

edges of the upper, comprising cutting means for severing the lacings, a guideway, a series of hook members arranged in the guideway with their hook portions in alinement to engage the lacings along those portions which cross the side edges of the upper, arms connected to the hook members extending across the series, and a spacing lever fulcrumed on the machine and connected at separated points along its length to 10 said arms.

15. A machine for operating upon a lasted shoe, the upper of which is stretched in close fitting relation to a last by one or more lacings passing through eyelets in opposite sides of the upper and across the outer surfaces at the side edges of the upper, comprising cutting means for severing the lacings, a guideway, a series of hook members arranged in the guideway with their hook portions in alinement to engage the lacings 20 along those portions which cross the side edges of the upper, a lever for changing the spacings of the hook members along the guideway, and an arm extending across the series rigidly connected to each hook member and pivotally connected to the spacing lever at equally separated points to cause the distance between adjacent hook members to remain the same when the spacing lever is moved.

16. A machine for operating upon a lasted 30 shoe, the upper of which is held stretched in close fitting relation to a last by one or more lacings passing through eyelets in opposite sides of the upper, comprising cutting means for severing the lacings, gripping means arranged to engage each 35 severed lacing, and means for removing the severed lacings from the gripping means.

17. A machine for operating upon a lasted 40 shoe, the upper of which is held stretched in close fitting relation to a last by one or more lacings passing through eyelets in opposite sides of the upper, comprising cutting means for severing the lacings, gripping means for each lacing, a

treadle for actuating the cutting means to sever the lacings and the gripping means to engage each severed lacing, and means for removing the severed lacings from the gripping means when the treadle is released.

18. A machine for operating upon a lasted shoe, the upper of which is held stretched in close fitting relation to a last by one or more lacings passing through eyelets in opposite sides of the upper, comprising cutting means for severing the 10 lacings, a hook member engaging each lacing and cooperating with the cutting means to sever the lacings, and a suction tube opening close to the hook members for removing the severed lacings from the hook members.

19. A machine for operating upon a lasted shoe, the upper of which is held stretched in close fitting relation to a last by one or more lacings passing through eyelets in opposite sides of the upper, comprising a series of cutting devices for severing the lacings, positioning members for engaging the lacings to locate the shoe in an operative position on the machine before the cutting devices act, and means for causing the cutting devices to sever the lacings successively while the lacings are engaged by said members.

20. A machine for operating upon a lasted shoe, the upper of which is held stretched in close fitting relation to a last by one or more 30 lacings passing through eyelets in opposite sides of the upper, comprising a series of cutting devices for severing the lacings, positioning members for engaging the lacings to locate the shoe in an operative position on the machine before 35 the cutting devices act, and means for gripping each lacing and actuating connections for causing the cutter devices to sever the lacings and the gripping means to act successively while the lacings are engaged by the positioning members.

JOSEPH FOSSA.
